UNITED STATES PATENT OFFICE.

RUDOLPH J. PANDURO, OF MILWAUKEE, WISCONSIN.

DESIGN FOR A CIGAR AND MATCH CASE.

SPECIFICATION forming part of Design No. 22,488, dated May 30, 1893.

Application filed April 26, 1893. Serial No. 471,987. Term of patent 7 years.

To all whom it may concern:

Be it known that I, RUDOLPH J. PANDURO, of Milwaukee, in the county of Milwaukee and State of Wisconsin, have invented and 5 produced a new and original Design for a Combined Cigar and Match Case, of which the following is a description, reference being had to the accompanying drawings, which are a part of this specification.

10 In the drawings, Figure 1, is a side elevation of my new case. Fig. 2, is an end elevation of the same case, and Fig. 3, is a medial transverse section of the case.

The leading feature of my design consists 15 of the elongated substantially cylindrical part A, having rounded and beveled or curved extremities, whose greatest elongation and lateral extension are along the medial meeting line B of the two halves of the cylindrical 20 part A, and the elongated laterally-extending

part C, formed on the part A, midway between its extremities, and integrally therewith.

The combined case is formed in two concave lids D and E which meet on the medial line B; the general contour of the case being 25 that of a cylinder with contracted rounded and closed ends and a medial extension C formed on the lid E, the part C having the appearance of a box formed on the cylindrical elongated separable part A. 30

What I claim is—

The design for a combined cigar and match case, substantially as herein shown and described.

In testimony whereof I affix my signature in 35 presence of two witnesses.

RUDOLPH J. PANDURO.
